MOTION PICTURES AND APPARATUS
THEREFORCharles Etzel, Philadelphia, Pa., assignor, by
mesne assignments, to Eizo Corporation, a cor-
poration of California

Application March 23, 1934, Serial No. 716,929

18 Claims. (Cl. 88—16.6)

This invention relates to motion pictures, and aims especially to reproduce in motion pictures the visual effects of depth, etc., characteristic of binocular vision: in other words, impressions of difference in the distances of different objects, of one being in front of another, and of the individual solidity or three-dimensional character of an object. While ordinary motion pictures can render diminution in size of objects, indistinctness of detail, and the shadow effects, etc., by which distance and solidity are in part instinctively inferred, they totally fail to render other very important factors or "clues" in our visual perception of depth and solidity, which depend on the cooperative vision of two eyes suitably separated.

An important feature of binocular vision is the automatic muscular coordination of the eyes commonly referred to as "convergency and divergency": the turning of the eyeballs in their sockets so as to direct (and converge) the axes of vision of both eyes on the spot or object that occupies the attention. From the different angular relations between the axes of vision required for objects at different distances, and the correspondingly different angular relations of the eyeballs and innervations of their controlling muscles, we subconsciously derive a sense of nearness and distance of objects. Another very important factor is what is known as "retinal rivalry": i. e., the fact that the left eye can see "further around to the left" of an object than can the right eye, and can thus often see more of the left side of a solid than can the right eye, and can see some portion of the background of an object which is hidden from the right eye,—and vice-versa. While the automatic adjustment of convergency and divergency permits an apperceptive synthesis of the slightly different images of the retinas of the two eyes, which results in our being normally unaware of the difference in these retinal images, yet this difference remains and is an important factor in our perceptions of depth, as well as of solidity.

In view of these considerations, it is easy to understand why picture producers have been unable to remedy the impression of flatness in motion pictures by means of costly "perspective" stage settings, special grouping of actors, and intricate light effects, and why exhibitors have had no better success by using over-dimensioned mirror lamps (as arc lamps with parabolic reflectors) in their projectors. Such exhibiting practices merely "burn out" the fine photographic effects and shadings of the film, overflow the screen with light, and cause serious eye-strain in theatre-goers; and stage-settings, groupings, and special lighting in production, etc., only improve the pictures in a two dimensional way.

I have found that the "flatness" of ordinary

motion pictures can be obviated, and the desired three-dimensional effects realized, by embodying suitable clues or characteristics of binocular vision in motion picture films themselves. For this purpose, in picture taking, a "visual analysis" and a multiple photographic record of the scene and action are made, in a manner analogous to the actions of two eyes in binocular vision. This record embodies one or (preferably) both of the usual "binocular clues": retinal rivalry and convergency-and-divergency. In projection, the diverse photographic components of the record are recombined in a manner analogous to the apperceptive synthesis of the two retinal images in ordinary vision, and so that the series of images on the screen evokes the usual mental response to the binocular clue(s).

In taking pictures according to my preferred procedure, the exposures to produce the multiple photographic record are not made as from one single point, but as from positions of a stereoscopic or binocular range corresponding (more or less nearly) to the normal pupillary distance,—which is some 2½ or 3 inches. In some cases, an exaggerated (or reduced) stereoscopic binocular range very different from the pupillary distance may be resorted to with good results; but ordinarily this will not be necessary. For each position of the range (actual or virtual) and for each exposure, the line of vision of the camera (the lens axis) is compensatively turned and directed (actually or virtually) so that the film-frame shall cover substantially the same field of vision, and substantially to the same (fixed) point or object of main interest in the subject or scene, thus compensating for the difference in point of view of the exposures, and also paralleling the convergency-and-divergency of binocular vision. The motion of the camera (actual or virtual) over the binocular range (and likewise its compensatory turning movement or oscillation) may be uniform or otherwise; and exposures made from a multiplicity of points in the range of motion may thus represent either equal or unequal shifts in the point of view: i. e., the "offset" from picture to picture may be either uniform or varied. With an ordinary motion picture camera, suitable light-deflecting and transmitting means (reflectors or mirrors) interposed in its line of vision may be used to effect (virtually) a transverse shift or an angular deflection of the line of vision—or both—in a manner equivalent to corresponding actual movement of the camera. A mirror, however, need only be turned half as much as the camera would have to be turned for the same effect of compensation.

In using a photographic record made according to my invention, the stereoscopic binocular film-frames or exposures (made as described from slightly different points of view) are pro-

jected on the screen in the succession in which they were made. The same persistence-of-vision which gives the illusion of continuous motion in ordinary motion pictures produces such an 5 ocular and mental synthesis of these slightly different film-frames as to give a clear-cut impression or illusion of binocular vision,—with all its usual three-dimensional effects.

While all this might seem to require the use 10 of two cameras (or a double camera) with suitably separated lens axes in picture taking, and a corresponding duplicity in exhibiting, I find that in practice such complications are not necessary. On the contrary, the necessary features may be 15 incorporated in a film which looks like ordinary motion picture film; and such film can be exhibited with the usual projection apparatus, without any special measures, and even by operators 20 entirely ignorant of its special character. In 25 other words, my invention can be successfully practiced with a single film strip bearing but one series of exposures or "film-frames". The exposures, moreover, can be taken with a single ordinary motion picture camera,—used, however, 30 in a special way such as hereinafter explained.

Various other features and advantages of the invention will appear from the following explanation and description of species thereof, and from the drawings.

30 In the drawings, Figs. I-Va are diagrammatic plan views illustrating the taking of motion pictures, with various different camera arrangements for the purpose.

Figs. VI and VII are diagrammatic illustrations 35 of film strip records taken in accordance with my invention.

Fig. VIII is a side view of one preferred form of apparatus for taking pictures according to my invention with a standard motion picture camera,—which is shown in full lines operatively 40 mounted on the apparatus.

Fig. IX is a corresponding plan view, without the camera.

Fig. X is a fragmentary plan view, on a larger 45 scale than Figs. VIII and IX, with certain parts in horizontal section.

Fig. XI shows a vertical section through the apparatus, taken as indicated by the line and arrows XI—XI in Fig. IX.

Fig. XII is a fragmentary view, showing a vertical section taken as indicated by the line and arrows XIII—XII in Fig. X.

Fig. XIII is a fragmentary detail view, partly 50 in vertical section as indicated by the line and arrows XIII—XIII in Fig. X.

Fig. XIV is a plan view with the upper camera and mirror-carrying structure removed, and certain parts in section.

Fig. XV shows a horizontal section through 55 the base of the machine, with its driving connections thus exposed.

Fig. XVI shows a fragmentary vertical section, taken as indicated by the line and arrows XVI—XVI in Fig. XV, illustrating part of the 60 operating connections to the camera.

Fig. XVII shows a similar fragmentary section, taken as indicated by the line and arrows XVII—XVII in Fig. IX, at the other end of the 65 connections to the camera.

Fig. XVIII shows a section taken as indicated 70 by the line and arrows XVIII—XVIII in Fig. VIII.

Figs. I-V show in plan a stage S set as a room 75 for the filming of a motion picture scene, and provided with a proscenium-arch or framed

opening P, a back-scene B containing a door b, and sloping side walls W, W. The principal object (or actor) O is shown at the front of the stage, substantially at the plane of the proscenium-frame P. In order to clarify certain points 5 regarding the field view, let us suppose that the shape and proportions of the proscenium-frame P correspond exactly to those of the film-frame in the motion picture camera C; that it is desired to show in the film-frame just what 10 appears in the proscenium frame, no more, no less; and that the camera C can be located at a position to accomplish this exactly: these, of course, are purely arbitrary conditions, that will rarely or never obtain in practice. Let us also 15 suppose that the preferred stereoscopic binocular range of camera positions for exposures is that marked d in Figs. I—V.

If exposures be made from each of the camera-positions C¹, C² in Fig. I, which are the distance d apart (on centers), with a single motion picture camera continually shifted back and forth transversely of its line of vision, and making its exposures at the positions C¹, C² in alternation, the result will be two sets of (negative) pictures, 20 alternating in a single series on the film, wherein the position of object O relative to its background (formed by backscene B) will be different. However, if the camera lens axes l¹, l² remain parallel when exposures are made from C¹ and C², 25 as shown in Fig. I, then convergency-and-divergency will not be incorporated in the sets of the pictures in any way; and if the proscenium-frame P exactly coincides with the film-frame in the pictures taken from the left-hand 30 position C¹, it will not do so in those taken from the right-hand position C²; on the contrary, these latter will show some of the frame P at the right, and will miss some of the scene within frame P at the left. In other words, the field of 35 view will be changed.

These defects can be substantially corrected, however, by a slight compensatory deflection or convergence of the lens axes l¹, l² for the positions C¹, C², as shown in Fig. II. With lens axes 40 l¹, l² thus pointed at substantially the very same object or spot O from both the positions C¹, C², both sets of pictures will have the proscenium frame P in coincidence with the film-frame, and will properly embody the clue of convergency-and-divergency. However, it is not necessary to 45 make all exposures from the extremes of the range d: on the contrary, some may be made from intermediate points. This is illustrated in Fig. III, where four camera positions C¹, C², C³, C⁴ 50 are shown, with the lens axes l¹, l², l³, l⁴ compensatively deflected accordingly, so as to be directed on the object O from each of these positions. The camera positions C¹, C², C³, C⁴, are not in a straight line, but on the arc of a circle 55 centered at the object O, so that all the pictures are taken at a constant distance from the object, and disparity of the pictures due to difference in distance is avoided. This is of advantage in making easier the mechanics of shifting the camera 60 back and forth, since the camera need not travel the whole range d in the very brief interval between successive exposures. Obviously, there may be a greater or less number of intermediate 65 exposure-positions in the range d. Moving slowly back and forth over the range d, the camera 70 need not be halted for the intermediate exposures, which are too brief to be blurred by comparatively very slow movement of the camera.

Using suitable light transmitting and deflect- 75

ing means such as reflectors (mirrors) interposed between the camera and the scene or object being filmed, the camera may or may not be shifted or turned: e. g., the mirrors may be shifted 5 or turned, or both, alike or differently, to produce the effect of shifting or turning the camera, or both. Fig. IV shows an arrangement in which the camera C is fixed on a stand or base 20 affording ways for the reciprocation of a carriage 10 22 whereon coacting "45°" mirrors M, m are mounted to turn about vertical axes 23, 23. These mirrors M, m receive the light from the subject or scene S and direct it into the camera C, deflecting the path of light from the scene to the camera and offsetting it laterally. A revolving crank disk 25 connected by a connecting rod 26 to the carriage 22 reciprocates the latter and its mirrors M, m through a range d, thus producing in 15 the camera C an effect similar to that of shifting 20 the camera itself. Either of the mirrors M, m may be pivotally connected at 27 or 28 to a link rod 29 which is in turn pivotally connected at 30 to a lever 31 fulcrumed at 32 on the stand 20, and pivoted at 33 to an arm 34 on the carriage 22. 25 Thus the mirror M or m is given a compensatory angular motion to and fro whose magnitude depends on the lever arms and thus on the relative position of the pivots 32, 30, 33. The effect of this is similar to that of turning the camera C,— 30 except, of course, that turning a mirror through a given angle is equivalent to turning the camera through double the angle. The mirror m or M that is not thus oscillated may be suitably held in a fixed (45° or other) position on the carriage 35 22.

Fig. V shows an arrangement in which the camera C is mounted on the carriage 22a so as to move to and fro with the mirrors M, m, either of which may have a compensatory angular motion. The mechanism is the same as in Fig. IV, 40 and its various parts and features are marked with the same reference characters, as a means of dispensing with repetitive description.

Fig. Va shows an arrangement more or less 45 similar to Fig. IV, but using only a single mirror M* and having the camera C pointed along the ways of the stand 20, transversely of the line of vision l. Accordingly, the path of light from the subject S to the camera C is deflected and 50 turned substantially 90° by the mirror M* when in the 45° position of Fig. Va. The mirror M* moves toward and from the camera C in a binocular range d transverse to the line of vision l, and may also have a compensatory 55 angular movement or swing, to and fro,—equivalent to turning the camera C back and forth. The mechanism is similar to that in Figs. IV and V, and its parts and features are marked with the same reference characters, as a means of dispensing with repetitive description.

Fig. VI shows a strip of film resulting from exposures made at the extremes C¹, C² only of the range d in Fig. II. Fig. VII shows a similar strip of film made with two additional, intermediate 65 exposures, so that the four exposures or film-frames correspond successively to the different positions C¹, C², C³, C⁴ in Fig. III. In both cases, it will be seen, the position of the door b in the back scene B varies relative to the object O,—this 70 variation being, of course, greatly exaggerated to make it apparent. In practice, the variation will be only enough to produce the retinal rivalry effect when the successive pictures are projected on the screen.

75 Figs. VIII—XVIII illustrate in detail a preferred

form of apparatus for the purpose of my invention, in which a motion picture camera C is reciprocated to and fro, transversely of the line of vision or lens axis of the camera, over a "stereoscopic binocular range", and can also be turned 5 or swung to and fro. A pair of "normally" parallel "45°" mirrors M, m are interposed between the camera and the scene or objective being photographed, to receive light from the scene or subject and direct it into the camera C. They 10 are mounted to move with the camera, as well as to turn or swing. The path of light from the subject to the camera C is deflected and offset by these mirrors M, m; and when they are turned through equal angles from the 45° position of 15 Fig. X, while remaining parallel, the deflection and length of the light-path from the scene or subject being photographed to the camera C are thereby altered: particularly, the length of the offset portion of the light-path between the mirrors M, m is changed. Each or either of these mirrors can be of single or multiple plane construction. The camera C is mounted (as by means of a dovetail socket 39) on a supporting structure or table 40 which also carries the mirrors M, m. The supporting structure or table 40 is movably mounted on a carriage 41 so that it can turn or swing relative to the carriage; and the carriage 41 is movably mounted to slide on a base or stand 42 so that it can reciprocate relative 20 thereto over any desired binocular range of movement. As shown in Fig. XI, the table 40 is pivoted (with antifriction ball bearings) about an upstanding stud 43 on the carriage 41, and is guided and steadied, so as to swing freely without 25 sidewise or tipping play, by V-faced guide segments 44 detachably mounted on the carriage, and cooperating with V-grooved guide rollers 45 mounted on the table 40, preferably with antifriction ball bearings. Fig. IX shows in dot-and-dash lines a standard motion picture camera C mounted on the table 40 in such position that the 30 axis of the pivot 43 about which the table 40 oscillates relative to the carriage 41 passes through the superjacent lens opening 59 of the 45 camera (Fig. VIII) and through the optical axis 40 of the lens. The base 42 is shown as a hollow cast metal structure, and is provided with parallel, opposed, internal V-faced guideways 46, 46 along its upper edges, each of which ways 46, 46 50 cooperates with a pair of V-grooved guide rolls 47, 47 mounted on the carriage 41. The base 42 is also shown provided with suitable means of support or attachment, such as feet 48 (Fig. VIII). The carriage 41 has the form of a plate 55 which partially covers the otherwise open top of the base 42, and protects the rollers 47 within the base. As best shown in Fig. XI, the dovetail socket 39 for mounting the camera C is in a part 59 adjustable in the direction of the lens axis 60 or line of vision of the camera along guideways 50 on the table 40.

As shown in Figs. XI and XII, the object or light-entrance mirror M and the camera or light-exit mirror m are removably mounted in holders 65 51, 52 which are rotatably mounted on upstanding bosses or hubs 53, 53 on the table structure 40, by means of pivot spindles 54, 55 rotatable in said bosses, preferably with antifriction ball bearings. Thus the mirrors M, m can turn freely relative to 70 the table 40, without looseness or possibility of side play of any kind. The mirrors M, m are enclosed in a sheet metal casing 51, detachably mounted on the base structure 40, and provided with an opening 58 in its rear side for the lens 75

opening or barrel 59 of the camera C, as well as with a much larger opening 60 to admit the light from the object or scene to be photographed. As shown in Figs. VIII, X and IX, a flaring hood 61 may be detachably mounted on the front of the casing 57 around the opening 60. The inside of casing 57 and hood 61 are preferably finished in dull black or other non-reflecting finish.

For actuating the carriage 41, there is in the base 42 a crank device 62 whose upright shaft axis 63 (preferably mounted in antifriction ball bearing) is driven by a worm wheel and worm gear 64, 65, enclosed in a casing 66 detachably mounted on the bottom of the casing 42. The worm shaft 61 (preferably also mounted in anti-friction ball bearings) may be driven or operated by any suitable means, such as a crank 68 connected to the shaft 61 through change speed gearing in a compartment or casing 69 on the base 42 (Fig. XV). A slide block 70 revolvably mounted on the crank pin 71 (with interposed antifriction ball bearings) cooperates with a guide groove or slideway 72 in the lower side of the carriage plate 41. As the crank 62 rotates at uniform speed, it reciprocates the carriage 41 (harmonically) over a range determined by the eccentricity of the crank pin 71 with reference to the shaft 63. To permit adjustment of the crank pin 71 to vary its eccentricity and thus adjust the amplitude of movement of the carriage 41, the crank pin 71 is mounted on a block 73 which is slidable radially along the crank arm 62. The block 73 may be adjusted and set in any desired radial position by means of an endless screw 74 whose ends are mounted in bearings at the inner and outer ends of the crank arm 62, and which is in threaded engagement with a downward projecting nut portion of the slide block 73. As shown, the outer endless screw bearing 75 is detachably secured to the crank arm 62. Beyond the bearing 75 is a polygonal-socketed sleeve 76 secured on the end of the screw 74 by a diametral pin 77. A polygonal "key" for turning the screw 74 may be inserted through an opening 78 in the base 42 when the crank arm 62 is turned to a suitable position to permit this.

The table 40 may be turned or swung to and fro relative to the carriage 41 by any suitable means, here shown as an operating connection between the table 40 and the base 42. As shown in Figs. IX, XI, and XIV, the connection comprises a follower slide block 79 (similar to the slide block 70) pivotally mounted at the lower side of the table structure 40 and engaging and cooperating in a cam groove or slideway 80 in a "tangent bar" member 81 located above the carriage 41 and extending (in the general direction of the carriage movement) from end to end of the base 42, transversely of the lens axis or line of vision of the camera. As shown in Fig. XIV, one end of the member 81 is pivoted to the base 42 at 82, beyond the extreme range of travel of the table 40, and its other end extends into a gear casing 83 detachably mounted on this end of the base 42. The end of the member 81 has rack teeth 84 which mesh with a worm 85 mounted in bearings in the removable ends of the gear casing 83. By turning the worm 85 one way or the other, the camway 80 can be adjusted to any desired angle of divergence relative to the direction of travel of the carriage 41, so as to oscillate or swing the table 40 about its axis 43, as the carriage reciprocates, through any desired amplitude of movement within the range of adjustment. As shown in Fig. IX, the shaft of the worm 85 has a

knurled knob 86 to which is clamped, by a screw 87, a spirally grooved barrel 88. The barrel 88 is graduated as shown in Fig. IX for cooperation with a pointer 89 on a slide 90 that slides in a suitable slideway in the gear casing 83, and has a projection 91 engaged in a spiral groove 92 of the barrel 88. This arrangement, it will be seen, permits very delicate adjustment of the inclination of the camway 80. Thus for any range of travel of camera C with carriage 41 and any distance of the principal object or point of interest in the scene or subject being photographed, table 40 and camera C are compensatively swung, reversely of the transverse movement, to keep the camera's line of vision (as deflected and determined by the mirrors M, m) directed toward the very same object in the scene. As the pivot-axis 43 for the swinging movement is at the lens barrel or opening 59,—at the "lens tube" of the camera, to use a generic term,—the swing of the camera introduces no complications; though it does not obviate the change in the effective length of the light-path from subject to camera that is produced by the (straight) transverse movement of the camera. In compensation for this, however, an opposite change in the effective length of the light-path is produced by the swinging of both mirrors M, m through equal angles concurrently with the transverse movement and swing of the camera C, as described hereinafter: i. e., as the mirrors swing while remaining parallel, the offset portion of the light-path from one mirror to the other is shortened or lengthened. Thus the virtual distance of the camera C from the object remains constant, as in Fig. III. The importance of thus keeping the effective length of the light-path from subject to camera substantially constant,—notwithstanding the transverse movement and swing of camera C with carriage 41 and table 40,—is, of course, to avoid noticeable changes in the apparent magnitude of objects in the picture. By the use of the knob 86 with its barrel 88 cooperating with the pointer 89, the camway 80 can be instantly adjusted to vary the amplitude of swing of the table 40 about its axis 43, even during the taking of a film and without interrupting either the operation of the camera C or the motions of the table 40 and the carriage 41. This allows of varying and adjusting the compensatory swing of the table 40 and camera C according to variations in distance of the principal object in the scene from the camera,—as when an actor walks toward the camera or away from it. This corresponds, of course, with the varying parallax in binocular vision according to the distance of the object from the observer. The adjustment is facilitated, of course, by suitable graduation of the scale on barrel 88 according to various distances of the object from the camera, as illustratively indicated by the numerals 7, 8, 15, 30, 40, 50, etc., shown in Fig. IX.

The light entrance or object mirror M and the light exit or camera mirror m (one or both) may be operated by any suitable means, such, for example, as an operating connection to the carriage 41. As shown in Figs. VIII, X, XI, and XII, a segmental gear 94 concentric with the table axis 43 is fixedly secured to the carriage 41 by said axis 43 and a screw 95. The segmental gear 94 meshes with an idler pinion 96 (preferably mounted with antifriction ball bearings) at the lower side of the table 40, and this pinion 96 meshes with a segmental gear 97 on a crank arm 98 detachably secured to the lower end of the spindle 55 of the camera mirror m, and concentric

with this spindle. As shown in Fig. XI, provision is made for angular adjustment of the crank arm 98 relative to the spindle 55, by means of a friction clutch connection comprising a conical cup member 100 keyed fast to the lower end of the spindle 55 and a conical hub 101 on the upper side of the crank arm 98. The hub 101 can be clamped tight in the cup 100 by any suitable means, such as a screw 102 taking into the lower end of the spindle 55, and associated washers 103, 104. The mounting 52 of the mirror *m* may be detachably secured to the upper end of the spindle 55 by a set screw 105: in Fig. XI, it is shown turned out of its normal angular relation 10 to the spindle 55, at right angles to the plane of the paper. The crank arm 98 is connected by a link rod 106 to a similar crank arm 108, of the same effective radius, which is keyed fast on the lower end of the spindle 54 of the light-entrance 15 mirror M. Mounting 51 of mirror M is detachably secured to the upper end of the spindle 54 by a set screw 109. As shown and indicated in Figs. XI and XII, the pivotal connections of the link rod 106 to the crank arms 98, 108 may be 20 provided with antifriction ball bearings, so that there shall be no back-lash. Through the connections just described, both mirrors M, *m* are turned relative to the table 40, as the latter swings, with a rotation opposite to that of the table relative to 25 the carriage 41, and at a rate depending upon the gear ratios or radii of the segmental gears 94 and 97. It is this turning or swinging of the mirrors M, *m* that is referred to above as compensating for the change in the effective length of the light-30 path due to the transverse movement of the camera. Obviously, this gear ratio may be changed practically as desired by substituting a larger or smaller idler 96 and corresponding changing of the segmental gear 94 and the crank arm 98 with 35 40 its gear 97. Obviously, also, the amplitude of swing of the mirrors M, *m* varies with the swing of table 40, since this directly produces the swing of the mirrors as described above.

When desired, the camera mirror *m* may be 45 disconnected from the crank arm 98 by means of the screw 102, etc., without interfering with the continued operation of the light-entrance mirror M. When the mirror *m* is thus disconnected, it may be locked in fixed 45° (or other 50 desired) position relative to the camera as shown in Fig. XIII, by means of a locking pin or bolt 110 movable longitudinally in a boss 111 on the table 40 and provided with a conical end for engaging a conical socket in an arm 112 on the 55 mirror mounting 52. When not in use, the bolt 110 may be retracted downward by its knob 113 against the resistance of a spiral spring 114 in the boss 111, so as to free the mounting 52 for unrestricted movement, and may be locked in 60 retracted position by giving it a 90° turn either way and then releasing it. In retracting the bolt 110, a diametral pin 115 fixed therein is withdrawn from a slot 116 in a downward extension of the boss 111; and when the bolt 110 is turned 90° and released, the pin 115 engages in a diametral notch 117 in the outer end of said 65 boss.

As shown in Fig. XV, the change speed gearing in compartment 69 on base 42 includes three gears 122, 123, 124 fast on the worm shaft 67, and three corresponding gears 125, 126, 127 fast on a sleeve 128 splined to the shaft 129 of the crank 68. The sleeve 128 may be shifted longitudinally of shaft 129, to bring any desired pair

of gears into mesh, by means comprising a crank shaft 130 mounted in a bearing boss on the side of the gear casing 69 and having an inner crank arm with a disc 131 at its upper end engaged in a groove between the gears 125, 126, and an outer 5 crank arm provided with an operating handle 132. As shown, the crank 68 is of variable radius, comprising a member 133 slidable in a diametral dovetail groove 134 in a fly-wheel disc 135 keyed fast to the end of the shaft 129. A 10 spring pressed ball catch 136 in a recess in the disc 135 is adapted to cooperate with any desired one of a series of conical socket recesses 137 in the inner side of the slide 133, to lock the 15 slide in various radial positions.

As shown in Figs. VIII, IX, and XV-XVIII, a flexible driving connection is provided for operating the motion picture camera C from the main drive shaft 129. For this purpose, there is a worm gear connection 140, 141 from the end 20 of the drive shaft 129 to a spindle 142 (Fig. XVI) mounted in (antifriction ball) bearings in the base 42 and connected as shown to a flexible shaft 143 in a flexible cover 144. To the other end of the cover 144 is secured a casing 145 25 (Figs. XVII and XVIII) which contains a revolving polygonal-socketed hub 146 adapted to engage the usual polygonal end of the operating shaft (not shown) of a standard motion picture camera. The socket hub 146 has helical 30 gear connections 147, 148 to a revolving sleeve 149 mounted (in antifriction ball bearings) in the casing 145 and splined at 150 to a spindle 151 connected to the flexible shaft 143. The casing 145 is provided with a split collar 152 35 which may be clamped by a screw 153 to a suitable boss (not shown) on the motion picture camera.

By suitable setting of the slideway 80 and selection of the gear ratio 94/97, various modes 40 of operation are possible. For example, with a fairly large inclination of the slideway 80, and a suitable gear ratio, the swing of the table 40 and camera C may be mainly or altogether relied on to compensate for the lateral shift of 45 the carriage 41, and the mirrors M, *m* may be swng together (remaining parallel, and with a rotation the reverse of that of the table) just enough to offset their change of direction due to the swing of the table. Or the camera mirror *m* may be released from the arm 98 and locked by the bolt 110 in fixed (45°) position relative to the table 40 and camera C; and then with a small inclination of the slideway 80, and a suitable gear ratio, the entrance mirror M 55 alone may be swng (relative to the table, and in the reverse direction) enough to compensate almost entirely for the lateral shift of the carriage 41—the swing of the table 40 (mirror *m* swng with it) necessary to actuate mirror 60 M making up the balance of compensation required. Or a slide setting and gear ratio intermediate those just indicated may be used. With the slideway 80 set parallel to the slideways 46, 46, there would be no turning of the table 40 or 65 of the mirrors M, *m*.

The gear ratios of the change speed gearing at 69 may be such as to provide for film speeds of 24, 48, or 72 film-frames per second when the crank 68 is turned so as to give one complete 70 back and forth movement of the carriage 41 every two seconds. Or if the gear ratios at 69 were such as to give a rapid table movement and an exposure at each end of the table travel, the harmonic movement of the table would give a 75

dwell of the camera sufficient for a comparatively long exposure. All of these supposed gear ratios, of course, are merely illustrative of what is possible.

5 Having thus described my invention, I claim:

1. A method of taking motion pictures affording the effect of three dimensions, which method comprises deflecting the path of light from the scene or subject being photographed to the camera, shifting the camera to and fro transversely over a stereoscopic binocular range, compensatively swinging the camera about an axis at its lens tube to keep its line of vision directed toward the same object in the scene, and concurrently varying the deflection of the light path so as to keep its length substantially constant, notwithstanding the other changes.

2. A method of taking motion pictures affording the effect of three dimensions, which method comprises deflecting and thereby offsetting the path of light from the scene or subject being photographed to the camera, shifting the camera to and fro transversely over a stereoscopic binocular range, compensatively swinging the camera about an axis at its lens tube to keep its line of vision directed toward the same object in the scene, and concurrently varying the length of the offset portion of the light-path so as to keep its total length substantially constant, notwithstanding the other changes.

3. Apparatus for taking motion pictures affording the effect of three dimensions comprising, in combination with a motion picture camera, means for shifting said camera to and fro transversely over a stereoscopic binocular range, means for concurrently and compensatively deflecting the line of vision of the camera according to its momentary position, and means for varying the relation between the deflection and the transverse shift of the camera as required by its momentary distance from the object, whether the latter is at rest, advancing, or receding, even during the operation of the camera and of said shifting and deflecting means.

4. In apparatus for taking motion pictures affording the effect of three dimensions, the combination of a supporting base and a motion picture camera mounted thereon for movement relative thereto as hereinafter set forth, means for shifting said camera to and fro on said base, transversely of its line of vision, over a stereoscopic binocular range, means for concurrently and compensatively swinging the camera about an axis at its lens tube to keep the line of vision of the camera directed toward the same object in the scene or subject being photographed, and means on the base connected to the swinging means for varying the swinging movement in relation to the transverse movement of the camera.

5. In apparatus for taking motion pictures affording the effect of three dimensions, the combination of a motion picture camera, means for shifting the camera to and fro transversely over a stereoscopic binocular range, means for deflecting the path of light from the subject or scene being photographed to the camera, and means for compensatively swinging the camera about an axis at its lens tube and varying the deflection of the light-path, so as to keep the line of vision of the camera directed toward the same object in the scene, and also to maintain the length of the light-path substantially constant, notwithstanding the other changes.

6. In apparatus for taking motion pictures af-

fording the effect of three dimensions, the combination of a motion picture camera, means for shifting the camera to and fro transversely over a stereoscopic binocular range, means for deflecting the path of light from the subject or scene being photographed to the camera, means for compensatively swinging the camera about an axis at its lens tube and varying the deflection of the light-path, so as to keep the line of vision of the camera directed toward the same object in the scene, and also to maintain the length of the light-path substantially constant, notwithstanding the other changes, and means operable while the camera and said shifting and swinging means are in operation for varying the swinging movement in relation to the transverse movement of the camera, according to variations in the distance of the object from the camera.

7. In apparatus for taking motion pictures affording the effect of three dimensions, the combination of a shiftable and swingable motion picture camera, swingable reflector means for receiving light from the subject or scene being photographed and directing it into the camera, means for shifting the camera to and fro transversely over a stereoscopic binocular range, means for compensatively swinging the camera and reflector means and thereby compensatively deflecting the line of vision of the camera so as to keep it directed toward the same object in the scene, and means operable while the camera and said shifting and swinging means are in operation for varying the swinging movement in relation to the transverse shift of the camera, for the purpose of keeping the line of vision of the camera directed to the object notwithstanding variation of its distance from the camera.

8. In apparatus for taking motion picture affording the effect of three dimensions, the combination of a base and a carriage sliding and reciprocable thereon through a stereoscopic binocular range, a supporting structure movably mounted on said carriage, for swinging motion about an axis relative to the carriage, means on said supporting structure for mounting a camera with its lens tube at the axis of swinging motion of said structure, and means for reciprocating said carriage and swinging said supporting structure as aforesaid.

9. In apparatus for taking motion pictures affording the effect of three dimensions, the combination of a base and a carriage sliding and reciprocable thereon through a stereoscopic binocular range, a supporting structure movably mounted on said carriage, for swinging motion about an axis relative to the carriage, means on said supporting structure for mounting a camera with its lens tube at the axis of swinging motion of said structure, and means operable while the camera and said last-mentioned means are in operation for varying the amount of swing of the supporting structure in relation to the reciprocation of the carriage.

10. Apparatus for taking motion pictures affording the effect of three dimensions, comprising, in combination with a motion picture camera, means for shifting said camera transversely over a stereoscopic binocular range, reflector means interposed in the line of vision of said camera, means for swinging said reflector means to thereby compensatively deflect the line of vision in correspondence with the transverse movement of the camera, means including a common drive for actuating said shifting and said swinging means, and operating said camera, and means

operable while the camera and said shifting and swinging means are in operation for varying the swing of said reflector means in relation to the transverse shift of the camera, according to variations in the distance of the object from the camera.

11. Apparatus of the character described comprising a carriage reciprocable transversely of the line of vision of a motion picture camera carried by said carriage, a supporting structure swingable on said carriage and provided with means for mounting the camera, reflector means swingable on said supporting structure, and means for reciprocating said carriage, swinging said supporting structure relative thereto, and swinging the reflector means relative to said supporting structure.

12. Apparatus of the character described comprising a carriage reciprocable transversely of the line of vision of a motion picture camera carried by said carriage, a supporting structure swingable on said carriage and provided with means for mounting the camera, reflector means swingable on said supporting structure, means for reciprocating said carriage, swinging said supporting structure relative thereto, and swinging the reflector means relative to said supporting structure, and means operable while the camera and said last-mentioned means are in operation for varying the swinging movement in relation to the transverse movement of the carriage, according to variations in the distance of the object from the camera.

13. Apparatus of the character described comprising a carriage reciprocable transversely of the line of vision of a motion picture camera carried by said carriage, a supporting structure swingable on said carriage and provided with means for mounting the camera, reflector means swingable on said supporting structure, and means actuated by a common drive for reciprocating said carriage, swinging said supporting structure relative thereto, swinging the reflector means relative to said supporting structure, and operating said camera.

14. Apparatus of the character described comprising a carriage reciprocable transversely of the line of vision of a motion picture camera carried by said carriage, a supporting structure swingable on said carriage and provided with means for mounting the camera, reflector means swingable on said supporting structure, and means for reciprocating said carriage and compensatively swinging said supporting structure relative thereto, and for reversely swinging the reflector means relative to said supporting structure to offset the swing of the latter.

15. Apparatus of the character described comprising a hollow base provided with guideways, a carriage on said base reciprocable along said guideways, actuating means in said base for reciprocating said carriage, a supporting structure swingable on said carriage and provided with means for mounting a motion picture camera, means forming an operating connection between said supporting structure and said base for swinging said supporting structure as said carriage reciprocates, reflector means for cooperating with said camera swingable on said supporting structure, and means forming an operative connection between the reflector means and said carriage for reversely swinging the reflector means relative to said supporting structure.

reflector means relative to said supporting structure as the latter swings.

16. Apparatus of the character described comprising a hollow base provided with guideways, a carriage on said base reciprocable along said guideways, actuating means in said base for reciprocating said carriage, a supporting structure swingable on said carriage and provided with means for mounting a motion picture camera, a camway mounted on said base above said carriage adjustable to varying inclinations relative to the movement of the latter, and follower means on said supporting structure cooperative with said camway to swing said supporting structure as said carriage reciprocates, reflector means for cooperating with said camera swingable on said supporting structure, and means forming an operative connection between the reflector means and said carriage for swinging the reflector means relative to said supporting structure as the latter swings.

17. Apparatus of the character described comprising a hollow base provided with guideways, a carriage on said base reciprocable along said guideways, actuating means in said base for harmonically reciprocating said carriage, a supporting structure swingable on said carriage and provided with means for mounting a motion picture camera, a camway mounted on said base above said carriage adjustable to varying inclinations relative to the movement of the latter, and follower means on said supporting structure cooperative with said camway to swing said supporting structure as said carriage reciprocates, reflector means for cooperating with said camera swingable on said supporting structure, and means forming an operative connection between the reflector means and said carriage for reversely swinging the reflector means relative to said supporting structure as the latter swings.

18. Apparatus of the character described comprising a hollow base with opposed internal guideways; a carriage on said base provided with rollers between and coacting with said guideways, and also provided with a slideway transverse to said guideways; drive means including a crank in said hollow base revolving in a plane substantially parallel with said guideways and coacting with said slideway to reciprocate said carriage along said guideways; means for adjusting the effective radius of said crank to vary the range of movement of said carriage; a supporting structure pivoted on said carriage and provided with means for mounting a camera, and coacting roller and arcuate guide means on said supporting structure and carriage for steadyng the one relative to the other; means forming an operating connection between said supporting structure and said base for swinging said supporting structure as said carriage reciprocates, with provision for adjustment to vary the swing; reflector means for cooperating with said camera swingable on said supporting structure; means forming an operative connection between the reflector means and said carriage for swinging the reflector means relative to said supporting structure as the latter swings; and a flexible connection from said drive means for operating a motion picture camera mounted on said supporting structure.

CHARLES ETZEL.
